UNITED STATES PATENT OFFICE

JOHN B. BAXTER, OF TROY, NEW YORK, ASSIGNOR TO COVERT MANUFACTURING COMPANY, OF WATERVLIET, NEW YORK, A CORPORATION OF NEW YORK

LINK

Application filed May 6, 1929. Serial No. 360,943.

This invention relates to improvements in links and more particularly to links of the split pivoted type.

An object of the invention is to provide an improved link of the general type referred to of simple practical construction, that can be manufactured at low cost and will be strong, durable and efficient in use.

A particularly important novel characteristic of the invention resides in the special construction and arrangement of means providing for locking the link members together against lateral displacement when the same are in closed relationship.

15 The invention, with other objects and advantages thereof, and the particular construction, combination and arrangement of parts comprising the same, will be understood from the hereinafter contained detailed description, when considered in connection with the accompanying drawings, forming part hereof and illustrating two embodiments of the invention.

In the drawings:

25 Figure 1 is a side elevation of a link constructed in accordance with the present invention, the link being closed.

Fig. 2 is an edge view.

Fig. 3 is a similar view with the members 30 in open position.

Fig. 4 is a detail side elevation of the link members separated.

Fig. 5 is a side elevation of a modified construction.

35 Fig. 6 is a top plan view of the modified construction illustrated in Figure 5.

Fig. 7 is a view similar to Figure 5, the link being shown open.

40 Fig. 8 is a detailed side elevation of one of the link members.

Fig. 9 is a detailed side elevation of the other link member.

45 While two specific embodiments of the invention are illustrated in the drawings, it will of course be understood that changes and modifications may be made in the particular constructions shown, and the invention may be embodied in other forms, as will appeal to those skilled in the art and falling within the scope of the appended claims, with-

out departing from the spirit of the invention.

Referring to a detailed description of the particular embodiment of the invention illustrated in Figures 1 to 4 of the drawings, the particular construction shown includes two similar members A and B, each of said members comprising a body or shank portion 1 with hook portions 2 at the ends thereof and disposed in a common plane therewith. The body or shank portion 1 of the members A, B, have rounded outer faces, the same being shown of elliptical form. The hook portions 2 each have an inner section or 55 butt portion 2^a circular in cross section and of substantially the same thickness as the body portion 1, and an outer section 2^b reduced in thickness at its inner side and provided with a flat inner side face 3, said outer sections being substantially semi-circular 60 shape in cross section, the same being shown split or reduced on their inner sides obliquely in the direction of their outer ends, the 65 said side face 3 of each hook portion 2 terminating at its outer end portion in a slight curve and being correspondingly curved at its inner end portion, as shown.

The members A and B are pivotally connected side by side at their body portions 1 by a transverse pivot 4 for relative lateral movement of the opposing hook portions 2. When the members A, B, are brought together, as shown in Figures 1 and 2 of the drawings, each pair of opposing hook portions 1 cooperate to form a closed eye, the outer reduced sections 2^b of the hook portions fitting against each other in overlapping relation. In Figure 3, the pairs of hook portions 2 are shown separated or in open 70 position. The body portions 1 of the members A and B are provided at their inner sides with smooth, flat bearing faces 5. The pivot 4 preferably, as shown, takes the form 75 of a separate pin extending through suitable bearings 6 in the body or shank portions 1 and being beaded at its ends.

In accordance with the present invention, in order to lock the hook portions 2 against lateral displacement when the same are in closed position, each hook portion 2 is pro-

vided with a shoulder portion or lug 7 and a recess 8, the arrangement being such that when the hook portions 2 are brought to closed position, as illustrated in Figures 1 and 2, the shouldered portions or lugs 7 on the hook portions 2 of one of the members A, B, enter the recesses 8 in the hook portions 2 of the other link member. The shoulder portion or lug 7 and recess 8 of each hook portion 2 are located at opposite sides thereof at the end portions of the outer reduced sections 2^b. The shoulder portion or lug 7 of each hook 2 is formed continuous with the thicker inner section or butt portion 2^a, said shoulder portion or lug extending forwardly from the outer end of the butt portion 2^a and projecting outwardly from the inner flat side face 3 of the outer section 2^b. The shoulder portion or lug 7, which is disposed adjoining the inner edge of the hook portion 2, has an inner flat side face 9 and a forward beveled face 10. The outer face of the shoulder portion or lug 7 is rounded corresponding with the adjoining rounded outer face of the hook portion. The flat side face 9 of the shoulder portion or lug 7 extends at an abrupt angle to the pivotal axis of the members A, B, the same being shown extending at substantially right angles thereto. Each of the recesses 8 is formed, as shown, with a flat side wall 11 to fit against the side face 9 of the shoulder portion or lug 7, and with an end wall 12 curved or beveled to correspond to that of the forward face 10 of the shoulder portion or lug 7.

The special construction of the shoulder portions or lugs 7 and recesses 8 affords efficient means for locking the hook portions 2 together against lateral displacement. The particular construction and arrangement avoids the necessity for recessing and weakening the outer reduced overlapping portions 2^b intermediate their ends. The locking shoulder portions or lugs 7 formed continuous with the thicker inner sections or butt portions 2^a of the hook 2 provides a strong construction and the particular contour and the location of the shoulder portions adjoining the outer ends of the inner sections or butt portions 2^a is such as to avoid breakage by contact with other parts in the use of the device, the resulting link structure being of a strong, durable, satisfactory nature that can be produced at low cost, the link members A, B, being easily formed by casting.

In the modified construction illustrated in Figures 5 to 8 of the drawings, the invention is shown applied to a snap hook. The construction includes a body or shank 13 having at one end a snap 14 and provided at its other end with a pivoted split link comprising a pair of similar members 15, 16, said members having body or shank portions designated respectively 17, 18, with hook portions 19, 20, at one end thereof. The body or shank por-

tion 17, of the member 15, is formed integral with the body or shank 13 of the snap device, the body or shank portion 18 of the other member 16 being pivotally connected by a pin or rivet 21 to the body or shank portion 17.

The hook portions 19 and 20 of the respective members 15, 16, have inner sections or butt portions and outer reduced sections, as shown, said hook portions being similar in form to the hook portions of the construction illustrated in Figures 1 to 4 of the drawings, and adapted when brought together to mate and form a closed eye at one end of the body or shank 13. The hook portions 15 and 16 are provided with shoulder portions or lugs 22 and recesses 23, the same being similar in construction and arrangement to the shoulder portions or lugs 7 and recesses 8 of the construction illustrated in Figures 1 to 4 of the drawings, and cooperating in a similar manner to lock the hook portions 15 and 16 against lateral displacement when the same are in closed position as illustrated in Figures 1 and 2 of the drawings.

What I claim is:

1. A link including two substantially similarly formed members, each having a body part with a hook portion at each end thereof, said members being pivotally connected at their body parts, the hooks of the respective members mating to form eyes and having overlapping outer sections reduced in thickness and provided with flat inner faces, each of said hook portions being provided with a shouldered portion on its inner side extending forwardly from its thicker inner section and with a recess in its outer end portion, the shouldered portions of the hook portions of one member engaging the recesses of the other member when the hook portions are brought together.

2. A link including two substantially similarly formed members each having a body or shank part with a hook portion at one end thereof, the body or shank parts being pivotally connected, the hook portions mating to form an eye and having outer overlapping sections reduced in thickness and provided with flat inner faces, each of said hook portions being provided with a shoulder portion on its inner side extending forwardly from its thicker inner section and with a recess in its outer end portion, the shoulder portion of one hook portion engaging the recess of the other hook portion when the hook portions are brought together.

3. A link including two substantially similarly formed members, each having a body or shank part with a hook portion at one end thereof, the body or shank portions being pivotally connected, the hook portions mating to form an eye and having outer overlapping sections reduced in thickness and provided with flat inner faces, each of said hook portions being provided with a shoulder por-

tion on its inner side extending forwardly from its thicker inner section substantially at right angles to the pivotal axis of the members and with a recess in its outer end portion, the shoulder portion of one hook portion engaging the recess of the other hook portion when the hook portions are brought together.

4. A link including two substantially similarly formed members, each having a body or shank part with a hook portion at one end thereof, the body or shank parts being pivotally connected, the hook portions mating to form an eye and each comprising an inner section substantially circular in cross section, and an outer section of less thickness than the inner section and having a flat inner face, each of the hook portions being provided with a shoulder portion on its inner side extending forwardly from its inner section and with a recess in its outer end portion, the shoulder portion of one hook portion engaging with the recess of the other hook portion when the members are brought together.

25 5. A link including two substantially similarly formed members, each having a body or shank part with a hook portion at one end thereof, the body or shank portions being pivotally connected, the hook portions mating to form an eye and each comprising an inner section substantially circular in cross section and an outer section of less thickness than the inner section and having a flat inner face, each of the hook portions being provided with a shoulder portion on its inner side extending forwardly from its inner section and with a recess in its outer end portion, said shoulder portions having rounded outer faces continuous with the rounded outer faces of said inner sections, the shoulder portion of one hook portion engaging with the recess of the other hook portion when the members are brought together.

In testimony whereof I hereunto affix my
45 signature.

JOHN B. BAXTER.
